US0D1065235S

(12) United States Design Patent (10) Patent No.: US D1,065,235 S
Caron et al. (45) Date of Patent:  Mar. 4, 2025

(54) DISPLAY SCREEN WITH GRAPHICAL USER INTERFACE OF A GAMING MACHINE

(71) Applicant: LNW Gaming, Inc., Las Vegas, NV (US)

(72) Inventors: Nancy Caron, Laval (CA); Francois Girard, Laval (CA); Joseph Rahamefy, Montreal (CA)

(73) Assignee: LNW Gaming, Inc., Las Vegas, NV (US)

() Term: 15 Years

(21) Appl. No.: 29/899,717

(22) Filed: Aug. 11, 2023

(51) LOC (15) Cl. 14-04

(52) U.S. Cl.

USPC D14/485

(57) CLAIM

The ornamental design for a display screen with graphical user interface of a gaming machine as shown and described.

DESCRIPTION

The FIGURE is a front view of a display screen with graphical user interface of a gaming machine showing our new design.

The peripheral broken line depicts a display screen and a boundary and forms no part of the claimed design. The broken lines depicting the remainder of the display screen with graphical user interface of a gaming machine form no part of the claimed design.
